UNITED STATES PATENT OFFICE.

HORTON BATCHELOR, OF SHERIDAN, WYOMING.

FURNACE.

1,296,906.

Specification of Letters Patent. Patented Mar. 11, 1919.

Application filed May 28, 1915. Serial No. 30,980.

To all whom it may concern:

Be it known that I, HORTON BATCHELOR, a citizen of the United States, residing at Sheridan, in the county of Sheridan and 5 State of Wyoming, have invented certain new and useful Improvements in Furnaces, of which the following is a specification.

This invention relates to furnaces and it has for its object the provision of an improved device of this nature embodying in 10 combination new and improved features of such a nature that a practically complete combustion may be had so that smoke will be prevented and the greatest economy in operation 15 will be secured.

Before proceeding with a detailed description of the construction and operation of the invention, it may be well to consider for a moment some of the problems presented in 20 the production of a furnace of this nature and to consider in a general and broad way the objects aimed at in the production of such a furnace. The errors made in the construction of combustion chambers heretofore 25 employed arose largely from the fact that the entire subject was treated as a purely mechanical problem when, as a matter of fact, it should have been treated as a chemical problem because it is only by securing 30 the proper chemical combination that complete combustion can be attained.

The combustion chambers heretofore employed have not given satisfactory results and in most cases there has been a great 35 loss of fuel placed in the combustion chamber and this loss has been entirely due to incomplete oxidation. With most of the devices at present in use, oxygen is supplied either by natural or forced draft, but in 40 none of them with which I am familiar has adequate means been provided for properly mixing the air with the fuel in such manner that a complete chemical combination upon combustion is the result. It may, 45 therefore, be stated that the purpose of this invention is to not only mix the air and the fuel, but that it has for its object the provision of means by which the quantity of air supplied may be varied in proportion to the 50 carbon and hydrogen content of the fuel. It is intended by the present invention to provide a structure in which the air and the fuel are first mechanically mixed in the proper proportions before being introduced 55 into the combustion chamber so that the

proper chemical combination to produce perfect combustion is instantly brought about when the mixture is subjected to the action of heat and not only is it intended to thus predetermine the proper mixture of the fuel 60 and air but the mechanical apparatus is so arranged that the proportion of air to the solid fuel may be varied in proportion to the carbon and hydrogen content of the fuel 65 rather than being varied in proportion to the volume of the fuel. The provision of such a structure as is herein outlined renders the process of combustion certain instead of haphazard. A further feature of the invention resides in providing a preliminary 70 combustion chamber in which a preliminary combustion takes place and a secondary combustion chamber in which combustion is completed in a manner hereinafter set forth. It will therefore be seen that in 75 carrying out the invention the processes of the chemist are closely followed in that the carbon and hydrogen content of the fuel is first determined, the fuel is pulverized to render the chemical action rapid and cer- 80 tain, the air is supplied in just the proper proportion to suit the carbon and hydrogen content of the material and thereby the result is rendered uniform and accurate.

The apparatus shown in the accompanying 85 drawing is merely intended to illustrate the principles involved and to show a preferred form of construction but it is to be understood that many modifications thereof may be resorted to without departure from 90 the invention.

In the accompanying drawing:—

Figure 1 is a side elevation of an apparatus constructed in accordance with the invention.

Fig. 2 is a partial sectional view thereof.

Fig. 3 is a detail perspective view of one of the air wheels.

Fig. 4 is a detail perspective view of one of the fuel feed wheels.

Fig. 5 is a vertical section through one of the air wheels and its associated parts.

Fig. 6 is a like view through the fuel feed wheel, and,

Fig. 7 is a detail view of one end of the 105 shaft upon which said wheels are mounted, showing a frictional adjusting device herein-after described.

Like numerals designate corresponding parts in all of the figures of the drawing.

Referring to the drawing, 5 designates an electric motor which drives an air compressor 6. This compressor serves to force air through a pipe 7 into a tank 8 where 5 the air is preferably compressed to about one pound pressure, though this may be varied as may be found to be desirable. The air passes from the air tank 8 through a pipe 9, a portion of which is disposed within 10 a furnace 10. The air as it passes through the portion of the pipe which is disposed within the furnace absorbs much heat which would otherwise pass through the stack and be wasted. The pipe 9 leads to branch 15 pipes 11. These branch pipes communicate with chambers 12 and 13 in which air wheels 14 are mounted upon a shaft 15 and in its passage past these wheels the air causes said wheels to rotate. The shaft 15 carries a fuel 20 feed wheel 16 provided with pockets 17 in its periphery. This fuel feed wheel is disposed within a passage 18 leading from the bottom of a hopper 19 to a mixing chamber 20. This mixing chamber is in communication 25 through conduits 21 and 22 with a primary combustion chamber 22^a. A secondary combustion chamber 23 contains a mass of porous material 24 of any suitable nature, though I prefer to use fire clay mixed with 30 30% of saw-dust which has previously been baked at a high temperature and then broken to proper size. Upon starting a furnace of this nature the air and fuel are forced into the primary combustion chamber and are ignited by any suitable means, such for instance, as a gas pilot burner 24^b but after the furnace is once started and the mass of material 24 becomes highly heated, it follows that the mixed air and coal will immediately enter into the proper chemical combination to produce perfect combustion upon 40 striking the highly heated mass and that this action will be continued as long as the motor acts to supply air to continue the feeding action of the fuel. It is apparent that after the parts become thoroughly heated and the fire is well started, preliminary combustion will take place in the chamber 22^a and that the partly consumed products 45 of combustion from said chamber will have to pass through the highly heated mass 24, on their way to the chimney where they will be completely consumed and the highest possible efficiency will be secured. Threaded 50 upon the end of the shaft 15 is a thumb-nut 25 which has a flange 26 arranged to bear against a boss 27 of one of the chambers 12 to thereby increase the friction upon shaft 15 so that it will require more or less air 55 60 to turn the shaft to feed a given quantity of coal into the mixing chamber 20, it being understood that the amount of air then supplied is determined by the carbon and hydrogen content of the coal as shown by a chemical analysis and in order that this amount

of air may be properly determined, I mark upon the shaft 15 a point 28 which is to be set with relation to graduations 29 upon thumb-nut 25 so that the carbon and hydrogen content of the coal being known, the 70 device may be immediately set to feed the proper proportion of air to the mixing chamber without reference to the volume of the coal and without continuous experiment in a haphazard manner in an endeavor to 75 secure the proper proportion of air.

While I have shown the apparatus operating in conjunction with a heating surface, it is apparent that it may be utilized in any relation where complete combustion is desired, as for instance, in steam boilers or the like. It makes no difference as far as the principle herein involved is concerned what type of furnace is employed because the problem is to produce perfect combustion 80 and any apparatus employing a combustion chamber when used as herein described and claimed comes within the spirit of the invention. 85

Having described my invention what I 90 claim is:—

1. The herein described method which consists of feeding coal in finely powdered form together with air under pressure into a mixing chamber of such shape that the 95 finely powdered coal will be agitated in suspension until the air and coal are intimately mixed, discharging such mixed air and coal into a preliminary combustion chamber in the presence of heat where preliminary 100 combustion takes place and then conducting the products of combustion from the preliminary combustion chamber to a secondary combustion chamber containing a mass of porous incandescent matter. 105

2. An apparatus of the character described, comprising an air supply conduit, an air driven wheel disposed therein, a powdered fuel feeding element connected to said wheel, a mixing chamber into which the air is discharged after it passes said wheel and into which the powdered fuel is discharged and wherein said powdered fuel is mixed with said air, means for conducting the air and powdered fuel after said mixture from 110 said mixing chamber to a combustion chamber and means for varying the amount of fuel delivered in proportion to the amount of air which passes said wheel, said means comprising a friction device for retarding 115 said wheel. 120

3. In a furnace construction a combustion chamber, a mixing chamber, a connection between the mixing chamber and the combustion chamber, a source of air under pressure, pipes leading from the source of air under pressure to the mixing chamber, a hopper for powdered coal, a pipe leading therefrom to the mixing chamber, a fuel feeding element disposed in said pipe, and 125 130

means actuated by the passage of air through said pipes for actuating said fuel feeding means.

4. In combination, a furnace provided 5 with a combustion chamber comprising a primary part and a secondary part, the secondary part containing a mass of non-combustible, porous material and the primary part being located therebeneath, a mixing 10 chamber, a connection leading from said mixing chamber to the primary part of the combustion chamber of the furnace, a source of air under pressure, pipes leading from the source of air under pressure to the mixing 15 chamber, a container for powdered coal, means for feeding coal from said container into the mixing chamber.

5. A structure as recited in claim 4, comprising in addition means for pre-heating 20 the air that is conducted to the mixing chamber.

6. A structure as recited in claim 4, wherein the pipes that conduct the air to the mixing chamber are in addition disposed 25 within the path of the waste products of

combustion from the combustion chamber to thereby pre-heat the air delivered to the mixing chamber.

7. A structure as recited in claim 4, wherein the connection from the mixing 30 chamber to the primary combustion chamber in addition leads from the lower part of the mixing chamber, and some of the air delivered to the mixing chamber is delivered at such a point that swirling currents of air 35 will be produced within the mixing chamber.

8. A structure as recited in claim 4, wherein said mixing chamber is in addition 40 substantially spherical in form and the connection that leads to the combustion chamber leads from the lower portion and laterally from the mixing chamber and some of the air delivered to the mixing chamber enters the same tangentially to thereby set up 45 swirling currents of air within said mixing chamber.

In testimony whereof I affix my signature.

HORTON BATCHELOR.
